SPRAY NOZZLE

William M. Cissell, Louisville, Ky., assignor to
W. M. Cissell Mfg. Company, Incorporated,
Louisville, Ky., a corporation of Kentucky

Original application November 22, 1943, Serial
No. 511,353. Divided and this application No-
vember 16, 1949, Serial No. 127,684

3 Claims. (Cl. 299--150)

1

This application is a division of application Serial No. 511,353, filed November 22, 1943, now abandoned.

My invention relates to improvements in valves, and has particular reference to valves employed on water-spray irons and water-spray guns used in laundries and dry-cleaning establishments.

This invention has for its principal object to so construct the component parts of the valve that they can be manufactured and readily assembled at low cost, expeditiously taken apart with conventional tools by the user for cleaning and/or replacement of the precision parts on which wear and fouling finally occur and at very low cost of time and money.

Another object of my invention is to provide a valve of the packless type in which a diaphragm seals the high pressure chamber from the actuating chamber.

A further object of my invention is to provide a valve having the seat for the valve stem adjacent the discharge end of the discharge orifice, so as to eliminate chambers or conduits etc. on the discharge side of the valve stem in which condensation may occur and cause dripping.

Another object of my invention is to provide a valve of simplified mechanical construction and of sufficient sturdiness to withstand the extreme operating conditions encountered in laundries and dry-cleaning establishments.

The advantages of these and other objects will become apparent as the following description is read in connection with the accompanying drawing, in which:

Figure 1 is a plan view of a pressing iron equipped with a valve made in accordance with the teaching of my invention, which iron is ordinarily referred to as a "water-spray iron";

Figure 2 is a side elevational view of Figure 1.

Figure 3 is a sectional view taken along lines 3-3 of Figure 1.

Figure 4 is a sectional view taken along lines 4-4 of Figure 1, and illustrated with the handle 7 and arm 7a removed.

Figure 5 is a partial sectional view on an enlarged scale showing the valve stem in engagement with the valve seat; and

Figure 6 is a similar partial sectional view showing the valve stem out of engagement with the valve seat.

With reference to the drawings, numeral 1 designates a conventional pressing iron, which iron may be either steam or electrically heated. Numeral 2 designates a conventional handle for the iron, and the numeral 3 designates a conduit

2

extending through the handle and connecting the valve assembly at the forward end of the handle.

In the preferred embodiment of my invention the conduit 3 is connected by a flexible hose to a chamber, which chamber is preferably constructed to collect condensation from a steam line, the chamber being arranged so that steam pressure is maintained upon the condensation collected in the chamber to provide the required pressure to discharge the condensation when the valve assembly is actuated. However, while this preferred construction and arrangement is described, it is to be understood that the teachings of this invention may be employed on valves intended for other purposes, and especially on valves for water-spray guns that are used independently of pressing irons, or for spray-guns generally, where it is highly desirable to provide uniform atomization and freedom from "drip" or "liquid blow-off."

With further reference to the drawings, it will be apparent that the valve assembly at the forward end of the handle 2 comprises a casing or main body 4; bonnet or plunger guide 5; adjusting cap 6; actuating handle 7; compression spring 8; reciprocating plunger 9; resilient diaphragm 10; valve-stem 11; removable nozzle 12; and removable filter plug 13.

Referring in particular to Figures 3 and 4, it will be apparent that the main body 4 is fixedly secured to the conduit 3, and has a duct 14 communicating with the interior of the conduit 3.

The removable filter plug 13 has a recess 15 communicating with the duct 14, and a filter medium 16, such as a fine wire mesh, closing the opening of the recess 15.

The removable plug 13 is threaded into the body member 4 and is provided with a suitable gasket 17 to seal the same to the body member. The plug 13 also has an external annular groove 18 communicating with a duct 19 in the main body, and an aperture 20 which provides a communication between the cavity 15 in the filter plug 13 and the annular groove 18. Thus, fluid pressure entering conduit 3 passes into the duct 14, through the filter medium 16 and into the cavity 15, thence through the aperture 20 into the annular groove 18 and then into the duct 19.

The duct 19 communicates with the valve chamber 21 and thereby the fluid pressure is conducted into the valve chamber 21.

The plunger guide 5, as shown in Figure 2, is secured to the body member 4 by a plurality of machine screws 22, and, as shown in Figures 3

and 4, the diaphragm 10 is disposed in a suitable recess in the plunger guide and clamped at its perimeter between the main body 4 and the guide member by a suitable ring formed on the upper surface of the body member.

The plunger 9 reciprocates in the plunger guide 5, and the compression spring 8 biases the plunger 9 downwardly. The adjustment cap 6 is threaded upon the plunger guide 5, thereby enabling the operator to adjust the spring pressure, and thus regulate the pressure required to actuate the lever 7. The lever 7 is pivotally mounted at 23 upon the plunger guide 5, and has an arm 7a extending through a slot in the side wall of the plunger guide, which arm engages the plunger 9 and raises the plunger when the lever 7 is depressed.

With reference to Figure 3, it will be observed that the arm 7a is rounded, and that the plunger 8 has a rounded cavity receiving the rounded end of the arm, thus providing a ball and socket connection between the members.

The valve stem 11 is threaded at its upper end, and this threaded portion extends through a central aperture in the diaphragm 10. The threaded portion of the valve stem is threaded into the lower end of the plunger 9, and this serves to secure the valve stem and plunger together and to clamp the diaphragm between juxtaposed faces thereof. The stem and plunger thusly assembled constitute a valve core.

The removable nozzle and valve seat 12 is threaded in the main body member 4 and is provided with a suitable gasket for sealing the same to the body member. It is also important to observe that the nozzle 12 has a central cylindrical cavity which receives the valve stem 11 and permits the same to reciprocate freely therein.

The lower end of the valve stem is slightly larger in diameter than its cylindrical shank, and the enlarged head portion preferably has diagonal slots cut in its cylindrical face as shown in Figures 5 and 6 to provide for the passage of liquid from the back side to the front side of the enlarged head. The diagonal slots provide a twirling action to the liquid and steam, and greatly increases atomization of the liquid discharged through the central orifice 24 in the nozzle 12. In this respect it is also important to observe that the external face of the valve seat in nozzle 12 adjacent the orifice 24 is concave to assist in the formation of a fog or mist or atomized liquid discharged from the orifice 24.

With particular reference to Figures 5 and 6, it is important to observe that the wall at the lower end of the nozzle 12 is very thin to provide a minimum distance through the orifice 24 from the valve seat on the inner face of the lower end, to the external concave face of the lower end. This feature is an important contribution in my valve construction as it entirely eliminates condensation drip, when the valve is closed, and, by reason of this, and the relatively small space around the valve stem in the cavity of the valve seat, and the comparative small size of the chamber 21, condensation or liquid blow-off is also eliminated when the valve is first opened, thus providing uniform atomization from the instant of opening of the valve and until it is entirely closed.

With reference especially to the three paragraphs next above it will be noted that the relation of orifice 24 in the nozzle 12, the cylindrical cavity thereof that receives the enlarged lower end or head of valve stem must be maintained in

concentric relation to provide the best formation of a fog or mist of atomized liquid discharged from the orifice. (The liquid serves as a lubricant). Therefore, precision dimensions of each

5 of the parts are necessary. No such requirements pertain to the bore of guide 5 and plunger 9 that slides freely therein without a lubricant. It will be observed that by reason of the radial movement or "play" between the guide and plunger, 10 with the valve stem and head depending therefrom, the head may center itself freely within the bore of the nozzle and of course without any 15 tendency to bind. Obviously, the diaphragm, being of rubber, offers no impedance to the "floating" relation of these parts.

This construction of the guide bearing in the nozzle, independent of the main body or housing comprised of casing 4 and bonnet 5, provides for the use of a superior metal qualified for long 20 service without corrosion, wear or burdening the product with prohibitive cost for material or precision processing. It should also be noted that this construction provides for the wall surrounding the orifice being concavely ground or lapped, through a simple inexpensive operation, to a knife edge thereby assisting materially in the attainment of the stated objects of this invention.

As also shown in Figures 5 and 6, the lower end 25 of the valve stem 11 has a plug 25 secured thereto that is preferably made from a phenol aldehyde condensation product, and, as illustrated in Figure 5, the lower face of this plug provides the sealing face on the valve stem 11 that engages the sealing face of the valve seat 12.

I claim:

1. In a valve comprising a casing having a chamber therein provided with an inlet and a spray orifice communicating therewith and a nozzle detachably mounted on said casing; said nozzle having a cylindrical cavity concentric with the chamber of said casing a wall in which said spray orifice is located and a valve seat surrounding said orifice; a bonnet having a chamber therein concentric with the chamber of said casing; a resilient diaphragm held at its periphery between the casing and bonnet for sealing the bonnet chamber from the casing chamber; the combination of an axially-movable plunger mounted within the bonnet chamber for slidable engagement therewith and having its lower end secured to the diaphragm; a movable valve stem positioned in the casing chamber and having its upper end secured to said plunger and the diaphragm and its lower end equipped with a head and plug-valve, 40 the head slidably engaged with said cavity so that the plug-valve will be engageable with the valve seat in said nozzle; a spring operatively associated with the bonnet and the plunger for biasing the plug-valve into engagement with the said valve seat to close the orifice; and an actuating member 45 operatively associated with the bonnet and plunger for operating the movable members against the action of said spring means to open said orifice.

2. A valve structure comprising a casing having an axial-cylindrical passageway therethrough; a discharge aperture in the wall thereof, an operating lever projecting into said chamber; a flexible diaphragm extending thereacross and dividing the casing into two chambers; a valve stem disposed in and slidably bearing against the cylindrical passageway of one of said chambers; a valve plunger disposed in and slidably bearing against the cylindrical passageway 50 55 60 65 70 75

of the other chamber and secured to said stem with the diaphragm gripped therebetween in axial alignment to provide a valve core, a spring operatively associated with said casing and said core for closing said aperture after the operating lever has raised said core to open the aperture.

3. A valve structure comprising a casing having an axial-cylindrical passageway therethrough; a flexible diaphragm extending thereacross and dividing the casing into two chambers; a discharge aperture in the wall of one of said chambers; a valve stem disposed in and slidably bearing against the cylindrical passageway of the last designated chamber; a valve plunger disposed in and slidably bearing against the cylindrical passageway of the other said chamber and secured to said stem with the diaphragm gripped therebetween in axial alignment to provide a valve core; an operating lever projecting into said other chamber; a spring operatively associated with said casing and said core for closing said aperture after the operat-

ing lever has raised said core to open the aperture.

WILLIAM M. CISSELL.
